Works, New Britain, Conn., a corporation of
Connecticut

Application December 6, 1950, Serial No. 199,475

6 Claims. (Cl. 292—332)

1

The present invention relates to a door latch and more specifically to a refrigerator latch mechanism having a manually retractable bolt which will be retained in a retracted position by a toggle linkage which is particularly adapted to shift the bolt to closed or latching position when engaged by a strike or keeper during closing of the door.

It is an object of the invention to provide an improved latch particularly adapted for cabinet and refrigerator installations.

Another object of the invention is to provide an improved latch mechanism which can be manually shifted to open position and which will automatically shift to latched position upon closing the door.

Another object of the invention is to provide a latch mechanism manually operable to the open position and automatically operable to the closed position to firmly engage a keeper element upon closing the door, whether the door is gently or firmly closed, and which will effect locking engagement should the door be slammed closed and thereby prevent rebounding of the door.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Figure 1 is a top plan view of a latch mechanism incorporating the features of the present invention, showing the latch mechanism as associated with a refrigerator door and cabinet, a fragment of which is illustrated in cross section.

Figure 2 is a rear view of the latch mechanism shown in Figure 1.

Figure 3 is a view similar to Figure 1 but shows the latch mechanism partially in section as secured to the door fragment when the latch bolt is in the open or retracted position.

Figure 4 is a cross sectional view of the latch mechanism taken along the line 4—4 of Figure 1 and viewed in the direction of the arrows.

For convenience of illustration, in the accompanying drawings the latch mechanism is indicated generally by the reference numeral 10 and the latch mechanism is shown as adapted for a refrigerator door 11.

The refrigerator door 11 is of double wall panel construction having an outer wall 12 spaced from an inner wall 13 which is hinged to the

2

refrigerator cabinet so that the door will close against the left hand vertical panel 14 of the cabinet. The door 11 carries a rubber-like seal or molding 15 about the periphery of its closing face so that the door opening of the cabinet will be sealed when the door 11 is closed.

The area between the outer and inner walls 12 and 13 of the door 11 provides ample space for mounting the latch mechanism 10 which is secured to the inner surface of the outer wall 12 by means of a vertically arranged mounting bracket 16. The mounting bracket 16 supports a latch frame 17 which comprises a unitary member having upper and lower frame plates 18 and 19, respectively, which journal most of the moving parts of the latch mechanism 10. The plates 18 and 19 are horizontally disposed in spaced relation to each other and each has a vertically struck deflected ear 20 which carry mounting bosses 21. The ears 20 engage an inwardly turned end section 23 on the outer wall 12 and are secured thereto by rivets, or the like, attached through the bosses 21.

As shown in Figure 2, the mounting bracket 16 has a generally rectangular aperture 24 which is in register with a similar aperture in the outer wall 12 of the door 11 to receive a handle mount indicated generally by the reference numeral 25. The mount 25 supports the vertically arranged handle grip 26 which shifts an actuating plunger 27 disposed in the mount 25. The handle mechanism forms no part of the present invention and it is, therefore, immaterial whether the handle is of the type that is rotated or of the push-pull type, so long as the plunger 27 is shifted inwardly when the handle mechanism is operated for the purpose of unlatching the door 11 from the cabinet panel 14.

When the actuating plunger 27 is advanced it strikes a buttress wall 28 vertically supported by a conversion link 29. The conversion link 29 comprises upper and lower bell crank plates 30 and 31 which are rotatably mounted in horizontally spaced parallel relation on a vertical pivot pin 32 journaled in spaced horizontal ears 33 struck from the mounting bracket 16. The conversion link, as its name would imply, converts the rectilinear thrust of the actuating plunger 27 into curvilinear motion for operating the other linkages of the latch mechanism 10 to be described.

The upper and lower plates 30 and 31 of the conversion link 29 have slots 34 for journaling a pivot pin 35 which is carried by the conversion link 29 at the end of the link opposite the but-

tress wall 28. As the conversion link 29 is pivoted about the pin 32, the pivot pin 35 describes a generally arcuate path. The pin 35 is embraced intermediate the upper and lower plates 30 and 31 by one end of a bell crank link 36 formed by upper and lower plates 37 and 38 horizontally disposed in substantially parallel relation to each other. The plates 37 and 38 rotate about a vertically arranged pivot pin 39 journaled in the upper and lower frame plates 18 and 19.

The bell crank link 36 has three lever arms, one of which has been described as embracing the pin 35 carried by the conversion link 29. Of the two remaining lever arms in the bell crank link 36, one journals a vertically disposed pin 40 within slots 41 in the upper and lower plates 37 and 38. The pin 40 is embraced intermediate the plates 37 and 38 by one end of a spring guide 42 which will be described in detail later. The remaining lever arm of the bell crank link 36 journals a third vertically disposed pin 43 in the upper and lower plates 37 and 38. The pin 43 is engaged intermediate the plates 37 and 38 in arcuate slots 44 in upper and lower plates 45 and 46 of a guide link 47 which is rotatably mounted between the upper and lower frame plates 18 and 19 by means of a vertically disposed pivot pin 48.

The pin 43 is also journaled by a horizontally disposed bolt blade 50 intermediate the plates 45 and 46. The bell crank link 36 rotates in a clockwise direction about the pivot pin 39 when urged by the conversion link 29 in response to the inward thrust of the actuating plunger 27. The clockwise movement of the bell crank link 36 carries the pin 43 in a clockwise moving arcuate path to shift the bolt blade 50 to the right as viewed in Figures 1 and 3. It is one function of the guide link 47 to guide the latch blade 50 in its movement in a gentle arcuate path to the right and a further guide for the bolt blade 50 is provided by a slot 51 in the link 50 which surrounds a guide pin 52 secured in the upper and lower frame plates 18 and 19.

In performing its function, the guide link 47 rotates about the pin 48 in a counterclockwise direction in guiding the bolt blade 50 to the right and the arcuate slot 44 in the link 47 cooperates with a rectilinear slot 49 in the bell crank 36 to determine the arcuate path of the blade 50 in cooperation with the pin 52 and the slot 51 in the blade. The guide link 47 also prevents inadvertent unlatching of the bolt in that it acts normal to the latching surface 50a of the bolt when latched. It will be seen, in comparing the position of the blade 50 in Figures 1 and 3, that although the blade is shifted a considerable distance to the right in the unlatching movement, it is also shifted upwardly.

The previously mentioned spring guide 42 is embraced by a coil spring 55 disposed between a vertical pin 56, carried by the upper and lower frame plates 18 and 19, and a plate 57, carried by the spring guide in a position normal thereto. The spring guide 42 has a bifurcated end section 58 which slidably engages the pin 56 so that flexing of the spring 55 will be caused when the spring guide is moved toward or away from the pin 56. Such movements in the spring guide 42 are caused by rotation of the bell crank 36 about its pivot pin 39. During clockwise or unlatching movement of the bell crank 36, the pin 40 describes an arc directed in a clockwise direction and carries the spring guide 42. The spring guide 42 and the arm of the bell crank 36 carrying the pin 40 provides a toggle mechanism

operable between the pins 39 and 56 having a fulcrum at the axis of pin 40. The toggle is in dead center condition when the pins 56, 40 and 39 are aligned. At dead center, the spring guide 42 will be shifted to the left to the greatest extent and the spring 55 will be under the greatest compression. The spring 55 will tend to buckle the aforescribed toggle mechanism about the fulcrum pin 40 as soon as the pin 40 is shifted from dead center. Thus, it will be seen that if the pin 40 lies below dead center the spring 55 will urge the latch mechanism 10 to the latched position of the blade 50 by counterclockwise rotation of the bell crank 36 and if the pin 40 is above dead center the spring 55 will urge the mechanism 10 to the unlatched position by clockwise rotation of the bell crank.

Thus it will be seen that a latch bolt such as the bolt 50 can be utilized without being encumbered by a spring. The bolt is nonetheless spring urged through a toggle mechanism.

In accordance with the present invention a strike or keeper 60 is affixed to the cabinet panel 14 and projects toward the door 11. The keeper 60 is L-shaped and carries a roller 61 at the end of the short leg of the L. When the door 11 is closed against the panel 14 the keeper 60 projects into the space between the door walls 12 and 13 through an aperture 62 in the rear wall 13. In the latched condition of the mechanism, as shown in Figure 1, the bolt blade 50 engages the keeper roller 61 to retain the door 11 in closed relation with the panel 14. In the unlatched condition of the mechanism, as shown in Figure 3, the bolt blade is shifted to the right so that it cannot engage the keeper roller 61 and the latch mechanism is in this position when the door 11 is open.

In closing the door 11 against the panel 14, the door will be swung toward the panel so that the keeper 60 will be thrust inside the door walls and the roller 61 will abut a pair of ears 63 struck from the spring plate 57.

It will be noted that the spring plate 57 is adjacent the fulcrum pin 40 and that thrust of the strike or keeper 60 against the spring plate 57 will shift the fulcrum pin 40 to a point below dead center as viewed in Figures 1 and 3. The spring 55 will urge a further shift in the toggle 42 and cause counterclockwise rotation of the bell crank 36 to shift the bolt blade 50 to the left to keeper engaging position.

As previously mentioned, the spring 55 will urge the toggle to either side of dead center position and it has been found desirable to limit the clockwise movement of the bell crank 36 so that the strike 60 will not have to shift the toggle elements a relatively great distance to reach dead center condition and beyond in the latching operation. Accordingly in the present mechanism a cam roller 65 is disposed between the upper and lower bell crank plates 37 and 38 on a vertical axis defined by a pin 66 journaled in the plates 37 and 38. The roller 65 engages a cam edge 67 on the end of the spring guide opposite the bifurcated section 58 when the spring guide approaches dead center condition of the toggle during clockwise rotation of the bell crank 36. The cam surface 67 has a projecting edge 68 which nests the roller 65 when the mechanism is shifted to a position slightly beyond center line condition in the clockwise movement of the bell crank 36. The nesting of the roller 65 in the cam projection 68 prevents further clockwise movement of the bell crank 36 and further off-center movement of the

toggle. Thus, when the door 11 is closed the strike 60 must shift the toggle linkage only a relatively short distance to the on-center condition and beyond. Shifting of the toggle in the afore-described manner is unopposed by the spring 55 because the engagement of cam 67 and roller 65 varies the effective length of the toggle link which comprises one arm of the bell crank 36. It will be seen that the effective length of the second toggle link which comprises the spring guide 42 will not vary because the pin 40 will be permitted to shift within the slot 41 in the bell crank 36. This means that the latch mechanism can be shifted to the latched condition even when the door is gently closed, insofar as little force is needed to cause the strike 60 to shift the toggle beyond dead center where the spring 55 will take control of the further latching movement. It should also be noted that if the door is forcibly closed or slammed the latching will occur in the same manner and the door will not rebound, because at the time the strike has shifted the toggle beyond dead center, the latch bolt 50 has been shifted to the left a sufficient distance to engage the keeper roller 61.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

We claim as our invention:

1. A refrigerator latch comprising a frame, a bolt having adjacent one end a forwardly engaging latching surface adapted to cooperate with the keeper, means between the frame and the other end of said bolt for supporting the bolt for rocking and longitudinal movements, a link pivoted to the frame at a pivot disposed at one side of the bolt and pivotally engaged with the bolt between the ends of said bolt and disposed at approximately a right angle to said latch engaging surface when the bolt is in latching position, a lever pivotally secured to said frame on a pivot disposed at the opposite side of the bolt and having an arm pivotally connected to the bolt intermediate the ends of the bolt, said lever having a second arm disposed at an angle to the first arm comprising a first toggle link, a second toggle link pivoted at one end to said first toggle link, means on said frame for pivotally and slidably supporting the other end of said second toggle link, said first and second toggle links forming a toggle, and a spring urging said toggle beyond one off-center position to maintain the bolt in latching position and for holding the toggle in another off-center position when the bolt is retracted.

2. A refrigerator latch comprising a frame, a bolt having adjacent one end a forwardly engaging latching surface adapted to engage a stationary keeper, means secured by the frame for supporting one end of said bolt for rocking and longitudinal movements, a link pivoted to the frame at a pivot disposed at one side of the bolt, means forming an engagement between said link and the bolt between the ends of said

bolt so as to cause pivotal movement of said link relative to said bolt, said link being disposed at approximately a right angle to said latch engaging surface when the bolt is in latching position, a lever pivotally secured to said frame for movement about a pivot disposed at the opposite side of the bolt and having an arm pivotally connected to the bolt intermediate the ends of the bolt, said lever having a second arm disposed at an angle to the first arm and comprising a first toggle link, a second toggle link pivotally and slidably connected at one end to the frame and pivotally connected at the other end to the first toggle link, said first and second toggle links forming a toggle extending substantially at right angles to the keeper when the bolt is in unlatched position and engageable with the keeper to be actuated thereby in the direction of off-center bolt latching position upon closing movement of the door manually operable means for shifting said toggle to an off-center position to retract the bolt and a spring acting on said toggle to maintain said bolt in latching position and for maintaining said toggle in off-center position when the bolt is retracted.

3. A refrigerator latch comprising a frame, a bolt having adjacent one end a forwardly engaging latching surface adapted to engage a stationary keeper, means between the frame and the other end of said bolt for supporting the bolt for rocking and longitudinal movements, a link pivoted to the frame at a pivot disposed at one side the bolt and pivotally engaged with the bolt between the ends of said bolt and disposed at approximately a right angle to said latch engaging surface when the bolt is in latching position, a lever pivotally mounted on said frame about a pivot disposed at the opposite side of the bolt and having an arm pivotally connected to the bolt intermediate the ends of the bolt, said lever having a second arm disposed at an angle to the first arm and comprising a first toggle link, a second toggle link pivotally and slidably connected at one end to the frame and pivotally connected at the other end to the first toggle link, said first and second toggle links forming a toggle, manually operable means for shifting said toggle to one off-center position and thereby cause retracting movement of the bolt, and a spring urging said second toggle link toward said first toggle link for holding the toggle in said off-center position, said toggle in said one off-center position being disposed substantially at right angles to the keeper and engageable with the keeper to be actuated thereby upon closing movement of the door to another off-center position causing latching movement of the bolt, said spring being operable to further the latching movement of the bolt and to maintain the same in latching position.

4. A refrigerator latch comprising a frame, a bolt having adjacent one end a forwardly engaging latching surface adapted to engage a stationary keeper, means between the frame and the other end of said bolt for supporting the bolt for rocking and longitudinal movements, a link pivoted to the frame at a pivot disposed at one side of the bolt and pivotally engaged with the bolt between the ends of said bolt and disposed at approximately a right angle to said latch engaging surface when the bolt is in latching position, a lever pivotally mounted on said frame about a pivot disposed at the opposite side of the bolt and having an arm pivotally connected to the bolt intermediate the ends of the bolt, said

lever having a second arm disposed at an angle to the first arm comprising a first toggle link, a second toggle link pivotally and slidably connected at one end to the frame and pivotally connected at the other end to said first toggle link, manually operable means for shifting said toggle to one off-center position and thereby cause retracting movement of the bolt, means for limiting movement of said toggle in the bolt retracting direction, said toggle in bolt retracting position being positioned at approximately a right angle to the keeper to be actuated thereby to off-center bolt latching direction upon closing movement of the door, and a spring urging said second toggle link toward said first toggle link for holding the toggle against the limiting means when the latch is in retracted position and for urging the toggle in further off-center bolt latching direction and for maintaining the same in latching position.

5. In a refrigerator latch having a frame and a latch bolt shiftably supported by the frame, a lever pivotally mounted on the frame and connected to the latch bolt intermediate the ends of the bolt, said lever having an arm comprising a first toggle link, a second toggle link pivotally and slidably connected at one end to the frame and pivotally and slidably connected at the other end to the first toggle link to form a toggle therewith in which the second toggle link is mounted for limited endwise movement with respect to the first toggle link when the toggle is in substantially on-center position, a spring carried by said second toggle link and biasing the same toward the first toggle link thereby urging the toggle toward off-center position to shift the latch bolt to latching position and toward another off-center position to releasably maintain the latch bolt in retracted position, manually operable actuating means for shifting said toggle to the retracted position, and means comprising a follower on said first toggle link and a cam on said second toggle link cooperating therewith to move the second toggle link endwise in a direction away from the first toggle link during movements of the toggle from on-center position to said other off-center position and permitting the second toggle link to return in a direction toward the first toggle link during return movement of the toggle to on-center position, whereby the effective length of the second toggle link is maintained substantially constant during movement of the toggle from said other off-center position to on-center position.

6. A refrigerator latch for use in a swinging door comprising a frame, a bolt having adjacent one end a forwardly engaging latch surface adapted to engage a stationary keeper, means between the frame and the other end of said bolt

for supporting the bolt for rocking and longitudinal movements, a link pivoted to the frame at a pivot disposed at one side of the bolt between the ends of said bolt, said link being engageable with 5 said bolt for pivotal movement relative thereto and being disposed at approximately a right angle to said latch engaging surface when the bolt is in latched position, a lever pivotally mounted on said frame about a pivot disposed 10 at the opposite side of the bolt and having an arm pivotally and slidably connected to the bolt intermediate the ends of the bolt, said lever having a second arm disposed at an angle to the first arm and comprising a first toggle link, a second toggle link pivotally and slidably connected at one end to the frame and pivotally and slidably connected at the other end to said first toggle link to form a toggle therewith in which the second toggle link is mounted for limited 15 endwise movement with respect to the first toggle link when the toggle is in substantially on-center position, a spring carried by said second toggle link and biasing the same toward the first toggle link thereby urging the toggle toward one off-center position to shift the bolt to latching position and toward the other off-center position to releasably maintain the bolt in retracted position, manually operable actuating 20 means for shifting said toggle to said other position, said toggle in said other position being positioned substantially at right angles to the keeper and engageable with the keeper to be actuated thereby to the off-center bolt latching position upon closing movement of the door, and means 25 comprising a cam on said second toggle link and a follower on said first toggle link for moving the second toggle link endwise in a direction away from the first toggle link during movements of the toggle from on-center position 30 to said other off-center position and permitting the second toggle link to return in a direction toward the first toggle link during return movement of the toggle to on-center position, whereby the effective length of the second toggle link is 35 maintained substantially constant during movement of the toggle from said other off-center position to on-center position.
